Patented Dec. 27, 1921.

UNITED STATES PATENT OFFICE.

AUGUST B. BECK, OF JERSEY CITY, NEW JERSEY.

GIRDLE.

1,401,861.

Specification of Letters Patent. Patented Dec. 27, 1921.

Application filed March 7, 1921. Serial No. 450,411.

To all whom it may concern:

Be it known that I, AUGUST B. BECK, a citizen of the United States, residing at Jersey City, in the county of Hudson and 5 State of New Jersey, have invented certain new and useful Improvements in Girdles; and I do declare the following to be a full, clear, and exact description of the invention, such as will enable others skilled in the art 10 to which it appertains to make and use the same.

My invention relates to improvements in ladies' girdles of the type constructed of elastic material and provided with hose 15 supporters.

One object of the invention is to provide a novel construction of girdle which will properly support the abdomen, even though the front part of the girdle may be pulled 20 downwardly to quite an extent by the front hose supporters.

A further object is to provide wide flat straps connecting the rear hose supporters with the elastic belt, said straps being positioned to pass vertically across the user's 25 hips whereby the rear hose supporters will exert a downward pull on the straps to hold the hips in an effective manner, preventing undesirable movement, for instance 30 when walking.

With the foregoing in view, the invention resides in the novel construction and association of parts hereinafter described and claimed, the descriptive matter being sup- 35 plemented by the accompanying drawings.

Figure 1 is a perspective view of a girdle constructed in accordance with my invention.

Fig. 2 is a horizontal sectional view as 40 indicated by line 2—2 of Fig. 1.

Fig. 3 is a detail horizontal section as designated by line 3—3 of Fig. 1.

In the drawings above briefly described, the numeral 1, designates an elastic belt 45 whose ends meet at the front of the girdle and are provided with suitable fasteners 2. A pair of horizontally elongated front flaps 3 are stitched at their outer ends to the front side of the belt 1 as seen at 4, preferably on somewhat diagonal lines as shown, while the inner ends of the flaps are provided with snap fasteners 5 by means of which they may be detachably connected. The flaps 3 are preferably formed of satin 55 although any other suitable material could be used, but it is essential that these flaps

shall be relatively inelastic since each one of them carries a pair of front hose supporters 6 which would greatly distort the flaps if they were of elastic material. Even 60 when the flaps are made of inelastic material, the hose supporters 6 pull them downwardly to quite an extent, but nevertheless the abdomen is properly supported by the portion of the belt 1 which spans 65 the space between the two lines of stitching 4. Were it not for this portion of the elastic belt, the abdomen would be allowed to bulge in an unsightly manner upon downward pulling of the flaps 3 by the hose 70 supporters 6.

The rear portion of the belt 1 is provided with a pair of wide flat straps 7 which depend from said belt in position to extend vertically across the user's hips. The lower 75 ends of these straps carry rear hose supporters 8 and when these hose supporters are attached to the stockings, they exert a downward pull on the straps 7, pulling the latter tightly across the hips and preventing 80 undesirable movement of the latter, for instance when walking.

The upper ends of the straps 7 preferably extend into and form part of the belt 1 as shown, this construction being more ad- 85 vantageous than if the straps were merely secured to the lower edge of the belt, since under the latter construction, the belt would be transversely stretched.

By constructing the device in or approxi- 90 mately in the manner shown and described, it may be easily and inexpensively manufactured and marketed, yet will be highly efficient and in every way desirable, and since excellent results have been obtained 95 from the details disclosed, such details may be followed if desired, but I wish it understood that within the scope of the invention as claimed, numerous changes may be made.

I claim:

1. A girdle comprising an elastic belt whose ends meet at its front, a pair of opposed inelastic flaps at the front side of the belt carrying hose supporters, means securing the outer ends only of said flaps to said 105 belt, means for detachably connecting the inner ends of said flaps with each other, and means for detachably connecting the ends of said elastic belt to each other behind and free of said flaps, whereby to effectively 110 support the abdomen independently of said flaps.

100

105

110

2. A girdle comprising an elastic belt whose ends meet at its front, a pair of opposed inelastic flaps at the front side of the belt carrying hose supporters, means securing the outer ends only of said flaps to said belt, means for detachably connecting the inner ends of said flaps with each other, means for detachably connecting the ends of said elastic belt with each other behind 10 and free of said flaps, whereby to effectively support the abdomen independently of said

flaps, a pair of wide flat straps secured to and depending from the rear portion of said belt in position to extend vertically across the user's hips, and rear hose supporters depending from the lower ends of said straps and adapted to pull downwardly thereon to exert holding pressure on the hips. 15

In testimony whereof I have hereunto set 20 my hand.

AUGUST B. BECK.
